UNITED STATES PATENT OFFICE.

ANDREW GRAFF, OF NEW YORK, N. Y.

PLATEN FOR TYPE-WRITING OR OTHER MACHINES.

SPECIFICATION forming part of Letters Patent No. 666,663, dated January 29, 1901.

Application filed March 15, 1900. Serial No. 8,760. (No model.)

To all whom it may concern:

Be it known that I, ANDREW GRAFF, a citizen of the United States, residing at New York, (Sheepshead Bay,) in the county of 5 Kings and State of New York, have invented certain new and useful Improvements in Platens for Type-Writing and other Machines; and I do hereby declare the following to be a full, clear, and exact description of 10 the invention, such as will enable others skilled in the art to which it appertains to make and use the same.

My invention relates to improvements in platens for type-writing and printing machines; and the objects of my improvements are, first, to provide a platen that is cheap, light, and durable, and, second, a platen that will lessen and deaden sound, and thereby prevent the annoyance occasioned by the 15 devices carrying the type striking against resonant surfaces of the wooden hollow platen now in use.

In carrying out my invention I take a piece of very heavy sole-leather, wet it thoroughly, 20 and then cut it into pieces of the required shape and size, as shown in Figures 1 and 7 of the drawings. The form of platen shown in Fig. 2 is the preferable one, but that shown in Fig. 6 can be made cheaper and placed 25 upon the market at a less cost. That shown in Fig. 6 I make of disks of leather cut into the required form from the waste pieces of scrap-leather.

I attain the objects of my invention by the 30 construction illustrated in the accompanying drawings, in which—

Fig. 1 is a plan view of the blank from which one of my forms of platen is made. Fig. 2 is a perspective view of the blank rolled 35 upon itself, riveted, and stitched. Fig. 3 is an end view of the platen shown in Fig. 2. Figs. 4 and 5 illustrate a modification. Fig. 6 illustrates another form of platen made from a number of disks. Fig. 7 shows one. Fig. 8 illustrates an end view 40 of the platen with the end metal plate removed; Fig. 9, the end metal plate, and Fig. 10 the ratchet-plate removed.

Similar letters refer to like parts throughout the several views upon Sheet 1 of the drawings, and similar letters of reference re-

fer to like parts throughout the several views upon Sheet 2 thereof.

The letter A refers to the blank from which the cylinder a is formed, and b nibs or projections upon the blank A, made integral therewith. I make a slight cut at the juncture of the nib or tag b with the blank A, so that the said nib or tag may be easily bent at an angle to the blank.

c represents the skived edge of the leather upon the flesh side of the blank A, and d the skived edge upon the grain or hairside of the leather blank.

e represents wooden rivets or pegs by which 65 the ends of the skived edges of the blank when rolled upon itself are fastened together, or the skived edges at the ends thereof may be secured together by stitches, as shown at f.

g represents a layer or cylinder of cork; h, 70 a layer or cylinder of felt; i, a core or roll of cotton or flocculent material within the layer or cylinder of felt f, and x the trunnion shown upon Sheet 2 of the drawings. The layer or cylinder of cork g I place within the 75 leather cylinder a. The layer or cylinder of felt h I insert within the layer or cylinder of cork g, and the core of cotton i or other like material I push or crowd within the cylinder of felt h.

b' represents nibs or tags or small pieces of leather sewed, cemented, or otherwise secured to the inside at the outer ends of the leather cylinder a before the layers or cylinders of cork and felt and the core of cotton 85 or like material are inserted within the leather cylinder a.

The letter M in Fig. 6 of the drawings shows a platen made of a series of leather disks.

In Fig. 7 I have illustrated by letter m one 90 of the series of disks which compose the platen M. (Shown in Fig. 6 of the drawings.) These disks are strung upon four metallic or wooden rods n and closely packed one against the other after either the end plate k or the 95 ratchet-plate l has been first firmly secured upon the said rods n by means of clamping-nuts, screws, or other fastening devices.

In the platen M, of the form shown in Fig. 6, I insert the layer or cylinder of cork g', 100 and within the said layer or cylinder I insert a layer or cylinder of felt h', and within the

said layer of felt I insert a core of cotton I' or other fleecy or flocculent material.

x' refers to the trunnion on Sheet 2 of the drawings.

5 The letter k (shown in Fig. 9 of the drawings) refers to the end metal plate secured to one end of the platen. (Illustrated in either of the forms upon Sheet 1 or upon Sheet 2 of the drawings.) l refers to the ratchet-plate 10 fastened or secured upon the opposite end of said platen in either of the forms shown upon Sheet 1 or Sheet 2 of the drawings.

From the construction of my platen herein shown and described it is obvious and manifest that the noise occasioned by striking devices carrying letters, characters, signs, &c., forcibly engaging my sole-leather platen will be greatly lessened, deadened, or entirely obviated over the platens now in use, which 20 cause sound usually distracting the attention of persons seated in rooms where they are used.

In making the platen shown in Fig. 2 of the drawings I cut from a size of sole-leather 25 the blank shown in Fig. 1 of the required shape, size, and length. I then wet the blank thoroughly and roll it. The edges of the blank thus cut out I skive thinly on both edges thereof, as shown in Fig. 1. One edge 30 I skive from the inside or flesh side of the leather. The other edge I skive upon the grain or hair side of the leather blank for the purpose of making a lap of about five-eighths of an inch in width. The blank of leather is 35 now ready to be put into the die and pressed into shape of a cylinder, as shown in Fig. 2 of the drawings. The skived edges of the blank after having been pressed into the shape of a cylinder I lap one over the other. 40 The said entire skived edges are then coated with a strong adhesive cement. The ends of the skived edges I then secure together by wooden pegs or rivets, or I may stitch the said edges together, as shown in Fig. 2 of the 45 drawings, and in this way the lapped cemented edges adhere very tightly and closely together, so that it is almost impossible to separate them. The cylinder at this stage of treatment is put into a press or die for the purpose 50 of shaping the tube and drying the cemented joint, thus making almost a seamless tube of leather. Neither wet nor dry atmosphere, heat nor cold will in any wise effect a separation of the joint thus made. After the blank of 55 sole-leather has been treated as above described, bent upon itself, skived edges cemented, riveted, and stitched it is then put into a lathe and turned true and even, after which the small pieces of leather, nibs, or 60 tags b' (shown in Figs. 4 and 5 of the drawings) may then be secured to the ends of the cylinder, on the inner surface thereof, by either riveting, sewing, or cementing the said pieces of leather, nibs, or tags thereto. By means

of the small pieces of leather, nibs, or tags b 65 and b' (shown in Figs. 1, 2, 3, 4, and 5) the metallic end plate and ratchet-plate are secured to the cylinder. In the cylinder shown in Fig. 2 the said end metal plates and ratchet-plates are secured by means of screws or 70 other like devices to the nibs or tags, and in the cylinder shown in Fig. 6 of the drawings the said end metal plate and ratchet-plate are secured to the cylinder shown in Fig. 6 by means of the rods n, having clamping- 75 nuts upon the ends thereof.

In finishing the cylinders I first sandpaper them thoroughly to make them smooth and even, and this is done in a lathe, after which the cylinders are coated with a coloring preparation of any desired color, and after the cylinders are dry they are burnished with a very hot burnishing-tool, the tool being hot enough to char the leather on its surface. After the surface of leather is burned or charred the 85 cylinders are once more put into a lathe and again sandpapered, after which they are once more burnished with a slightly-warmed burnishing-iron, which gives to the cylinders a polish, and they are then ready for use. 90

What I claim as my invention, and desire to secure by Letters Patent, is—

1. As an article of manufacture, a platen comprising a blank having attaching nibs or tags and a core. 95

2. As an article of manufacture a platen comprising a blank having integral attaching nibs or tags and a core.

3. A platen provided with a leather exterior, a cotton interior and felt and cork respectively over the latter, and clamping devices for the platen. 100

4. A platen provided with a leather cylinder having nibs or tags, a core of cotton and cylinders of felt and cork respectively, over the 105 core, clamping-plates connected with said nibs or tags and trunnions to support the platen.

5. A platen provided with attaching nibs or tags, cylinders of cork and felt respectively, a core of cotton, clamping-plates connected 110 with said tags or nibs and supporting-trunnions.

6. The process herein described of making platens for type-writing and printing machines consisting in cutting out the blank of 115 sole-leather, skiving the edges thereof, rolling it upon itself to form a cylinder, riveting, stitching and cementing the skived edges of the blank, drying the cylinder, charring the surface thereof, smoothing the charred surface and burnishing and polishing the same. 120

In testimony whereof I have hereunto affixed my signature in presence of two witnesses.

ANDREW GRAFF.
